(57) **CLAIM**

The ornamental design for a table trencher, as shown and described.

DESCRIPTION

FIG. 1 is a front left side perspective view of a first embodiment of a table trencher.

FIG. 2 is a top view thereof.

FIG. 3 is a bottom side view thereof.

FIG. 4 is a front side view thereof.

FIG. 5 is a rear view of thereof.

FIG. 6 is a left side view thereof.

FIG. 7 is a right side view thereof.

FIG. 8 is a front left side perspective view of a second embodiment of a table trencher.

FIG. 9 is a top view thereof.

FIG. 10 is a bottom side view thereof.

FIG. 11 is a front side view thereof.

FIG. 12 is a rear view of thereof.

FIG. 13 is a left side view thereof; and,

FIG. 14 is a right side view thereof.

The dashed broken lines in the drawings depict features of the table trencher that form no part of the claimed design. The dash-dot broken lines separate the part for which we claim protection from the part shown in dashed broken lines for which we do not claim protection.
